UNITED STATES PATENT OFFICE.

JOHN E. CLIFFORD, OF STOCKTON, CALIFORNIA, ASSIGNOR TO RICHARD RUSSELL SMITH, OF STOCKTON, CALIFORNIA.

VALVE MECHANISM FOR INTERNAL-COMBUSTION ENGINES.

1,179,698.

Specification of Letters Patent. Patented Apr. 18, 1916.

Application filed May 18, 1912, Serial No. 698,169. Renewed September 28, 1915. Serial No. 53,160.

To all whom it may concern:

Be it known that I, JOHN E. CLIFFORD, a citizen of the United States, residing at Stockton, in the county of San Joaquin and State of California, have invented new and useful Improvements in Valve Mechanism for Internal-Combustion Engines, of which the following is a specification.

The present invention relates to improvements in rotary valves for internal combustion engines, the object of the invention being to provide such rotary valve mechanism which will be simple in construction, noiseless in operation, contain few parts, and those easily manufactured, which can be removed, cleaned, if necessary, and replaced, with an expenditure of little time and labor, and which will by its own operation be maintained comparatively cool notwithstanding the passage therethrough of the exhaust gases of the engine.

In the accompanying drawings, Figure 1 is a side view of a four-cylinder internal combustion engine to which my invention is shown as applied; Fig. 2 is an end view thereof; Fig. 3 is an enlarged longitudinal section thereof on the line 3—3 of Fig. 4; Fig. 4 is a transverse section thereof on the line 4—4 of Fig. 3; Fig. 5 is a side view of the rotary valve detached; Fig. 6 is a perspective view of a clutch ring, or union, therefor.

Referring to the drawing, 1 indicates a crank case of a four-cylinder internal combustion engine in which rotates the shaft 2 of said engine. Secured upon said crank case are the casings 3 of the cylinders of said engine formed with water jackets 4. Formed on said casings are boxes 5 for a worm shaft 6, to one end of which is secured a sprocket wheel 7 engaging a sprocket chain 8, which also engages a sprocket wheel 9 secured upon the shaft of the engine. Said sprocket chain 8 also engages a sprocket wheel 11 on the shaft 12 of the magneto generator 13 for supplying current to the spark plugs of the engine, the casing 14 of which generator is secured to a flange of one of the cylinder casings. Said worm shaft carries worms 16 which mesh with worm wheels 17 (see Fig. 4) rotating between ball-bearings 18; and each having, on the side next the cylinder, a central recessed portion 19 and an outer annular raised portion 20 formed with diametrically opposite radially extending under-

cut grooves 21. Said grooves engage beveled feathers 23 formed on one side of a clutch ring 24, on the other side of which ring are formed feathers 26 at right angles to the feathers 23 and which engage grooves 27 in an annular end of a rotary tubular valve 28.

The relation of each worm wheel 17 to the corresponding worm 16 is such that the tubular valve 28 makes one revolution for every four revolutions of the engine shaft 2. Screwed into the end of the valve to close the same is a plug 29 having in its outer side a hexagonal recess to facilitate its being screwed into the valve. Screwed centrally into said plug and extending therefrom is a stem 30 having at its outer end a spherical knob 31. Engaging said knob and thereby drawing the valve to the wheel 17 is a spring clip 32 bolted, as shown at 33, to the wheel 17 in the bottom of the recess 19. The spring clip is formed with a flaring mouth to facilitate the entry of the knob thereinto. Said valve 28 is formed with an inner tube 34 and with an outer tube 35, spaced apart to provide an annular conduit 36, the outer tube extending beyond the inner tube at the end thereof connected to the plug, but connected integrally with said inner tube at the other end. At said latter end said outer tube 35 is of increased thickness, so as to form an annular shoulder 37 abutting against a wall 38 of an annular supply chamber 39, and the terminal portion of the valve is again of increased thickness, so as to form a second annular shoulder 40 abutting against an outer wall 41 of the casting 3. The shoulder 37 of the rotary valve serves to prevent the passage of gases between the annular gas supply chamber 39 and space between the outer tube 35 and its bearing, and in like manner the shoulder 40 prevents the ingress of air or exhaust gases into said annular gas supply chamber 39. By forming the shoulder 40 and the outer wall 41 very thin, a cooling effect of the gases of the annular gas supply chamber upon said wall and shoulder is procured, that is not obtained otherwise. Between said inner and outer walls 38, 41, is formed the annular gas supply chamber 39, extending entirely around the outer tube of the valve, said supply chamber deriving its supply of combustible mixture by a conduit 43, which leads through the wall 41 of the casting. Into a

recess in said outer wall around said conduit 43 fits the end of a hollow fitting 44, with which communicates a pipe 45 of the manifold. Fitting in a recess in said wall 41 around the open end of the tubular valve is the head 46 of a hollow fitting 47 connected to an exhaust pipe 48. Between the head 46 and the wall 41 is interposed a gasket 49 of asbestos which serves also as a 10 heat insulator and the inner side of which is lined with a thin sheet 40 of copper. Said fittings are held in place by means of a bar 51, through which passes a post 52, the inner end of which is screwed into the cylinder casting, which bar 51 is firmly pressed against the outer sides of said fittings by a wing nut 62 screwed on to said post.

The annular gas supply chamber 39 communicates with the annular conduit 36 between the inner and outer tubes of the valve by means of a circular series of rectangular apertures 53 formed in said outer tube, and from said annular conduit 36 the combustible mixture can flow into the cylinder by 25 one of two elongated ports 54 in said outer tube, when said port 54, by the rotation of the tubular valve, is brought into register with that end of a pair of conduits 55 in the cylinder casting which leads to the interior 30 of the corresponding cylinder. By the same conduit 55 the exhaust gases can flow out of the cylinder through one of two exhaust conduits 56 leading to the interior of the inner tube from the outside of the valve, 35 thence flowing to the interior of the fitting 47, and thence to the exhaust pipe 48. The elongated ports 54, as likewise the exhaust conduits 56, are arranged diametrically opposite to one another and thus prevent the 40 warping of the valve that would be caused by the heating thereof with exhaust gases were the arrangement otherwise, as, for instance, if only one port 54 and one conduit 56, were used.

45 The ports 54 and conduits 56, are, of course, formed in the rotary valve in such angular relations, that the valve will move at the proper time to supply combustible gases to the cylinders for explosive combustion, and to permit the escape of the waste gases resulting from combustion.

It will be observed that by reason of the inner tube being spaced from the conduit 55 by the annular conduit for the combustible mixture, the waste gases, passing outward through said inner tube, are preventing from highly heating the outer wall of the valve and the part of the head of the cylinder in contact therewith; while, at the same 50 time the flow of the combustible mixture around said inner tube prevents the same from becoming excessively heated by said waste gases.

By reason of the inlet conduit for the 55 combustible gases surrounding the exhaust

conduit for the combustible gases, said gases are heated by the passage of the exhaust gases, and are thus thoroughly vaporized and brought to a perfect condition for immediate combustion when supplied to the 70 engine.

An important advantage of my invention consists in the construction whereby the valve tube can be removed bodily, inspected and cleaned, if necessary, and replaced, by 75 the mere unscrewing of a nut, and the removal of a loose fitting.

When the engine is in operation the back pressure from the exhaust and the suction from the intake are sufficient to keep the 80 shoulders of the valve firmly seated against their seats. Means otherwise provided for holding the valve in position are intended for use only during the other periods of the engine cycle. It is not desirable to apply 85 pressure to the hot or exhaust end of the valve for this purpose, and for this reason the draw clamp 32 is provided at the opposite end of the valve. It is to be observed that the construction of the loose joint will 90 be such that, when the valve is in the position to be driven home in the valve seat it will also be in the position without further attention on the part of the assembler, to register with the cylinder conduits. 95

I claim:

1. In an internal combustion engine, the combination of two parallel internal combustion cylinders having adjacent heads, and provided with a rotary valve seat, adjacent to their heads, each cylinder being connected with said seat by a passage for the admission and exhaust of gases, a rotary valve in said seat its plane of rotation being parallel with that through the axes of the 105 cylinders, and comprising an inner tube and an outer tube extending beyond the inner tube and separated therefrom by an annular space, said tubes being both closed at the same end, the inner tube being open at the other end to exhaust, and means at said other end for connecting the annular space between the tubes with a source of supply of combustible mixture; said valve being provided with two diametrically opposite 110 passages leading to said seat from the inner tube, and two diametrically opposite passages leading to said seat from the space between the tubes, all the ends of said passages adjacent to said seat being located to 115 register in succession, in the rotation of the valve, with the passage connecting said seat with each cylinder. 120

2. In an internal combustion engine, the combination of two parallel internal combustion cylinders having adjacent heads, and provided with a rotary valve seat, adjacent to their heads, each cylinder being connected with said seat by a passage for the admission and exhaust of gases, and a rotary 125

valve in said seat its plane of rotation being parallel with that through the axes of the cylinders, and comprising inner and outer tubes, both closed at the same end and separated by an annular space, the inner tube being at the other end open to exhaust, the valve seat being formed at said other end with a gas supply chamber, and said outer tube being formed at said other end with a circumferential series of holes for conducting fuel gas from said supply chamber to said annular space, said valve being provided with two diametrically opposite passages leading to said seat from the inner tube, and two diametrically opposite passages leading to said seat from the space between the tubes, all the ends of said passages adjacent to said seat being located to register in succession, in the rotation of the valve, with the passage connecting said seat with each cylinder.

3. In an internal combustion engine, the combination with a cylinder having a conduit, of means for supplying a combustible mixture, a rotary valve located in the head of the cylinder and comprising inner and outer tubes, a valve casing surrounding the valve and formed at one end with an annular supply chamber, the same end of the outer tube being formed with a plurality of openings for admitting combustible mixture from the annular supply chamber to the annular space between the inner and outer tubes, the inner tube communicating with the atmosphere at the same end of the valve, said valve being formed with conduits communicating with its outer side respectively from the interior of the inner tube and from the annular space between the inner and outer tubes, and means for rotating said valve from the engine shaft.

4. In an internal combustion engine, the combination with a cylinder of the engine having a conduit through its head, of means for supplying a combustible mixture to said engine, a rotary tubular valve consisting of inner and outer tubes, the inner tube communicating with the atmosphere, and the annular space between the inner and outer tubes communicating with said means, said valve being formed with conduits communicating with its outer side respectively from the interior of the inner tube and from the annular space between the inner and outer tubes, a wheel driven from the engine shaft, and means for transmitting the rotation of said wheel to one end of said valve permitting said valve to be readily detached longitudinally therefrom, said valve casing and valve having respectively a seat and annular shoulder, and means for holding the shoulder to its seat.

5. In an internal combustion engine, the combination with a cylinder having a conduit, and means for supplying combustible

mixture, of a rotary valve for regulating the supply of said mixture, and the escape of waste gases from the cylinder, means located at the end of said valve remote from exhaust for maintaining the valve in position, and means, detachably engaging said end of the valve, for rotating the valve, said valve being detachable by a longitudinal movement only from the means for rotating it.

6. In an internal combustion engine, the combination of an internal combustion cylinder provided with a valve seat in its head, and connected with said seat by a passage, and a valve rotatable in said seat having inner and outer tubes, spaced apart, the inner tube forming the wall of the exhaust conduit and being open at one end to exhaust, and the valve seat being formed with a supply chamber around the outer tube and communicating through the outer tube with said space between the tubes, the valve being provided with passages leading to said seat from the inner tube and space.

7. In an internal combustion engine, the combination with a cylinder of the engine having a conduit through its head, of means for supplying a combustible mixture to said engine, a rotary tubular valve consisting of inner and outer tubes, the inner tube communicating with the atmosphere, and the space between the inner and outer tubes communicating with said means, said valve being formed with conduits communicating with its outer side respectively from the interior of the inner tube and from the space between the inner and outer tubes, a wheel driven from the engine shaft, and means for transmitting the rotation of said wheel to one end of said valve, a valve casing in which said valve rotates and having a chamber with which said supplying means and space communicate, said valve and valve casing having on each side of, and closely adjacent to, the communication with said space respectively an annular shoulder, and a seat upon which the shoulder can make a close joint, and means for holding said shoulders to their seats.

8. In an internal combustion engine, the combination of two parallel internal combustion cylinders having adjacent heads, and provided with a rotary valve seat, each cylinder being connected with said seat by a passage for the admission and exhaust of gases, a rotary valve in said seat, and comprising an inner tube and an outer tube separated by an annular space, said tubes being both closed at the same end, the inner tube being open at the other end to exhaust, and means at said other end for connecting the annular space between the tubes with a source of supply of combustible mixture, said valve being provided with two diametrically opposite passages leading to said

seat from the inner tube, and two diametrically opposite passages leading to said seat from the space between the tubes, the ends of each pair of diametrically opposite passages being located to register alternately, in the rotation of the valve, with the passage connecting said seat with each cylinder.

In testimony whereof I have hereunto set my hand in the presence of two subscribing witnesses.

JOHN E. CLIFFORD.
